UNITED STATES PATENT OFFICE.

EDWARD L. FORD, OF YOUNGSTOWN, OHIO.

PUDDLING-FURNACE.

1,212,929.

Specification of Letters Patent. Patented Jan. 16, 1917.

Application filed September 22, 1915. Serial No. 51,999.

To all whom it may concern:

Be it known that I, EDWARD L. FORD, a citizen of the United States, residing at Youngstown, in the county of Mahoning and 5 State of Ohio, have invented a new and useful Improvement in Puddling-Furnaces, of which the following is a full, clear, and exact description, reference being had to the accompanying drawings, forming part of 10 this specification, in which—

Figure 1 is a sectional elevation of a puddling furnace embodying my invention. Fig. 2 is an end view of the same, and Fig. 3 is an elevation of the detachable cover.

15 The present invention is an improvement upon the puddling furnace described and claimed in my Patent No. 564,276 of July 21st, 1896.

One object of the present invention is to 20 improve the door or cover at the end of the furnace.

The furnace described in my said patent is provided with a plate or cap member carried by a burner and having its edges separated from the edges of the furnace opening 25 sufficiently to permit of the escape of the products of combustion.

The present invention is designed to provide a door or cover carried by the furnace 30 itself to rotate and move therein, but which is readily removable to permit of the discharge of the puddled ball. This door or cover is provided with a central hole through 35 which the fuel is introduced and through which the waste gases also escape. The present improvement permits of the removal from the furnaces of a larger ball than is possible in the old furnace, since in that construction if the door was made very 40 large, the heat losses around its perimeter were so great that difficulty was experienced in keeping up the necessary heat in the furnace and an increased amount of fuel was required.

45 Another object of the present invention is to provide improved means for carrying the load of the furnace when in its horizontal balling position, and which will automatically adjust itself to the varying diameter 50 and angle of the axis of the furnace.

Referring to the accompanying drawings, in which I have shown a preferred embodiment of my invention, and which will now be described, the numeral 2 designates the 55 furnace proper which is in general similar to that of my said patent.

3 designates the trunnions on which the furnace is journaled; and 4 the gearing for rotating the furnace about its own axis. Any suitable means, such as those shown in 60 my previous patent, may be employed for tipping the furnace.

In accordance with my present invention, I make the opening 5 at the end of the furnace preferably of substantially the full internal diameter of the furnace body and normally close the same by means of a cover or door member 6 which seats closely against the mouth of the opening. This cover or door member is formed with an approximately 65 central opening 6^a through which the fuel is introduced by means of a suitable supply pipe 7 and around the nozzle of which pipe the waste gases escape from the furnace. Said member is rigidly secured to the furnace to 70 rotate and move therewith, but the securing means are of a readily removable character so as to permit said member to be quickly detached. Any suitable fastenings may be employed for these purposes, such as the removable keys 8.

It will be readily seen that the construction provides for the formation and removal of a puddled ball of maximum diameter while, at the same time, there is very little 85 opportunity for undue escape of heat from the interior of the furnace.

In the operation of these furnaces, it has been found that great strains are thrown upon the trunnions of the furnace during 90 the balling operation, due to the fact that the furnace body or its supporting portion is not perfectly cylindrical and therefore does not perfectly adapt itself to a fixed support such as has been heretofore employed, consequently, as the furnace is rotated, it is subjected to wobbling movements 95 of a nature to strain the furnace. To obviate this, I provide a support which preferably consists of the two rotatable wheels 100 9 journaled in a bracket 10 which is pivoted to a supporting member at 11 and which member is in turn swiveled on a vertical axis 12 in the support 13.

14 designates a ring or track surrounding 105 the furnace pot near its end.

It will be readily seen that by the combined action of the horizontal pivot at 11 and the vertical pivot 12, the supporting wheels will readily adapt themselves to irregularities and variations in the position 110 of the furnace as it is rotated during the

balling operation. In this manner a constant support for the furnace is provided which greatly relieves the trunnions.

I do not desire to limit myself to the particular embodiment of my invention which I have herein shown and described, and it will be obvious that various changes can be made in the details of construction and arrangement of the various parts, thus the 10 cover or top member may be constructed and secured in different ways, the details of the universal support may be changed, and other changes may be made.

I claim:

15 1. A puddling furnace having one end permanently closed and the other end provided with a large opening, said furnace being carried by supports which permit it to rotate and tip respectively on different axes, an annular cover detachably secured to the said open end and rotating with said furnace, said cover acting to decrease the opening of said end during the puddling operation, but which can be removed to permit of the removal of the finished puddle ball, and a fuel pipe arranged to discharge fuel through the opening of said cover into the furnace, the opening being arranged to allow the products of combustion to escape 30 therethrough, substantially as described.

2. A puddling furnace having one end permanently closed and the other end provided with a large opening, said furnace being carried by supports which permit it to 35 rotate and tip respectively on different axes, an annular cover detachably secured to the said open end and rotating with said furnace, said cover acting to decrease the opening of said end during the puddling operation, but which can be removed to permit of the removal of the finished puddle ball, and a pipe projecting into the opening of said cover and arranged to discharge fuel into 40

the furnace, the opening being arranged to allow the products of combustion to escape 45 therethrough, substantially as described.

3. A rotary tipping puddling furnace, carried by supports which permit it to rotate and tip respectively on different axes, said furnace having one end closed and the other end provided with a fuel inlet, an outlet for the products of combustion, and a single supporting structure arranged underneath the free end of the furnace, said support being rotatable in a horizontal plane 55 and having a plurality of supporting rollers, substantially as described.

4. A rotary tipping puddling furnace carried by supports which permit it to rotate and tip respectively on different axes, said furnace having one end closed and the other end provided with a fuel inlet, an outlet for the products of combustion, and a single supporting structure arranged underneath the free end of the furnace, said support 60 being arranged to tilt in one plane and rotate in another plane and having a plurality of supporting rollers, substantially as described.

5. A rotary tipping puddling furnace carried by supports which permit it to rotate and tip respectively on different axes, said furnace having one end closed and the other end provided with a fuel inlet, an outlet for the products of combustion, and a single supporting structure arranged underneath the free end of the furnace, said support 75 being arranged to tilt in a vertical plane and having a plurality of supporting rollers, substantially as described.

In testimony whereof, I have hereunto set my hand.

EDWARD L. FORD.
